FOCUSING MASS SPECTROMETER
 Giichi Iwata, 1209 Sugano, Ichikawa City, Japan
 Filed Mar. 11, 1957, Ser. No. 645,282
 Claims priority, application Japan Mar. 31, 1956
 5 Claims. (Cl. 250—41.9)

The present invention relates to a mass spectrometer of the highest transmission by utilizing a combination of special electric and magnetic fields.

If the transmission is defined as the percentage of all ions emitted from an ion source in all directions, which will reach an ion detector or collector, the transmission of any known mass spectrometers and ion separator invented up to present never attained the optimum value of 100%. This applies also to the trochoidal mass spectrometer invented by Bleakney and Hippel, Phys. Rev., vol. 53, p. 521, 1938, since ions emitted substantially in one plane only reach the ion detector.

The combination of special electric and magnetic fields of the present invention will produce a perfect focusing effect for ions of like mass-to-charge ratio regardless of their initial velocity and position.

It is therefore an object of this invention to provide a method and apparatus having a perfect focusing effect for ions of like mass-to-charge ratio regardless of their initial velocity and position.

Electric and magnetic fields utilized are, with respect to a Cartesian coordinate system x , y and z , as follows:

Uniform magnetic field: Components of magnetic field strength (0, 0, $-B$).

Hyperboloidal electric field which is expressed in terms of an electric potential:

$$\varphi = \frac{V}{4l^2}(-x^2 - y^2 + 2z^2)$$

B , magnetic field strength.

V , potential difference.

l , defining the longitudinal dimension of electrode.

Equations of motion of an ion:

$$m \frac{d^2x}{dt^2} = -eB \frac{dy}{dt} + \frac{eV}{2l^2} x$$

$$m \frac{d^2y}{dt^2} = eB \frac{dx}{dt} + \frac{eV}{2l^2} y$$

$$m \frac{d^2z}{dt^2} = -\frac{eV}{l^2} z$$

m , mass; e , charge; and t , time.

Introducing a new variable

$$\xi = x + iy, i = \sqrt{-1}$$

One combines the first and the second equations into a single equation as follows:

$$m \frac{d^2\xi}{dt^2} = ieB \frac{d\xi}{dt} + \frac{eV}{2l^2} \xi$$

Calculating

$$eB/2m = \omega, \sqrt{\frac{eV}{ml^2}} = \nu$$

for simplicity, equations of motion become

$$\frac{d^2\xi}{dt^2} = 2i\omega \frac{d\xi}{dt} + \frac{\nu^2}{2} \xi$$

$$\frac{d^2\xi}{dt^2} = -\nu^2 \xi$$

Calculating $\xi = e^{i\omega t} \xi_0$, one gets an equation for ξ

$$\frac{d^2\xi}{dt^2} = -\lambda^2 \xi$$

5 where λ stands for

$$\sqrt{\omega^2 - \frac{\nu^2}{2}}$$

Hence the solution of equations of motion will be

$$\xi = \xi_0 \cos \lambda t + \left(\frac{d\xi}{dt} \right)_0 \frac{\sin \lambda t}{\lambda}$$

$$z = z_0 \cos \nu t + \left(\frac{dz}{dt} \right)_0 \frac{\sin \nu t}{\lambda}$$

where quantities marked by the suffix 0 denote their initial values at $t=0$.

Returning to ξ , one gets

$$\xi = e^{i\omega t} \left[\xi_0 \cos \lambda t + \left(\frac{d\xi}{dt} \right)_0 - i\omega \xi_0 \right] \frac{\sin \lambda t}{\lambda}$$

If one puts $\lambda = \nu$, therefore

$$\omega = \nu \sqrt{\frac{3}{2}}$$

one gets at $t=\pi/\nu$

$$\xi = -e^{i\pi} \sqrt{\frac{3}{2}} \xi_0 = e^{i\pi} \left(\sqrt{\frac{3}{2}} - 1 \right) \xi_0$$

$$z = z_0$$

because of $\sin \nu t = \sin \pi = 0$, and $\cos \nu t = \cos \pi = 1$.

The three quantities are defined as follows:

$$\omega = \frac{eB}{2m}$$

a half value of Larmor frequency.

$$\nu = \sqrt{\frac{eV}{ml^2}}$$

frequency of vertical oscillation of ion.

$$\lambda = \sqrt{\omega^2 - \frac{\nu^2}{2}}$$

All ions starting from a point (ξ_0, z_0) converge therefore to its image point

$$\left(e^{i\pi} \left(\sqrt{\frac{3}{2}} - 1 \right) \xi_0, -z_0 \right)$$

regardless of their initial velocity

$$\left(\frac{d\xi}{dt} \right)_0, \left(\frac{dz}{dt} \right)_0$$

55 thus achieving the perfect focusing that has never been achieved in ion-optics. After each lapse of time π/ν , the ions will be periodically focused to successive image points of the starting point.

In other words, the transmission is 100% if an ion 60 source and an ion current detector or collector are set at the points (ξ_0, z_0) and their image points respectively.

Paths of ions projected in the xy -plane are shown in FIG. 1. And the projections of an ion source and an ion current detector or collector on the xy -plane are 65 numbered 102 and 103 respectively. Because of the relation

$$\pi \left(\sqrt{\frac{3}{2}} - 1 \right) = 0.2247\pi = 40.5^\circ$$

70 the angle which said projections 102 and 103 form with the vertex 101 of the ion source and the ion current detector or collector on the xy -plane is 40.5° .

Generally speaking ions which do not have the desired mass-to-charge ratio travel along arcuate paths similar to that of ions which have the desired mass-to-charge ratio, but do not converge at any point, thus rotating around the z-axis.

Ions that start from the point (ξ_0, z_0) and have special mass-to-charge ratios $3e/m$ and $e/2m$, e/m being the desired mass-to-charge ratio, will be equally focused to their image points

$$(\xi_0 e^{i\pi/\sqrt{2}}, -z_0) \text{ and } (-\xi_0 e^{i\pi\sqrt{3}}, z_0)$$

respectively regardless of their initial velocities.

The relation of electric and magnetic fields follows from the relation

$$\lambda = v \text{ and } \omega = v \sqrt{\frac{3}{2}} \text{ as } \frac{e}{m} B^2 l^2 = 6V \text{ or } \frac{m}{e} = \frac{B^2 l^2}{6V}$$

The general principle of perfect focusing is as stated above.

Its essential task is to combine the uniform magnetic field with the hyperboloidal electric field.

Means for producing the above electric and magnetic fields are numerous.

An example of a mass spectrometer utilizing the above electric and magnetic fields is shown in the drawings, where:

FIGURE 1 is a diagram showing the contemplated mathematical configuration of the ion path in the device of the invention.

FIG. 2 is a perspective view of a simplified schematic representation of the mass spectrometer, with portions cut away and some elements removed;

FIG. 3 shows a side view of a portion of an electrode;

FIG. 4 shows a model of a hyperboloid of one sheet;

FIG. 5 shows a horizontal view of a portion of an electrode;

FIG. 5(A) is a cross-sectional view of the element shown in FIG. 5.

FIG. 6 shows a sectional view of the ion source and the ion current detector or collector;

FIG. 7 shows a schematic diagram of required voltage supply and a potential distribution inside the electrode.

The same reference characters denote the same parts throughout the specification and the several views of the drawings.

Referring more specifically to the drawings, FIG. 2 in particular the apparatus proper is shown enclosed in a cylindrical tank 1 which is evacuated. The z-axis is shown passing through point 101 in FIG. 1. Within the boundary of the tank 1 a uniform magnetic field is maintained in parallel with the symmetrical axis of an electrode which produces a hyperboloidal electric field. Said electrode consists of two parallel circular rings 2 and 3 supported by six bronze uprights 4, a net 5 of conducting copper wires connecting said rings 2 and 3 and a pair of parallel insulating discs 6 and 7, facing each other, perpendicular to the direction of said magnetic field, and equipped with a plurality of concentric conducting rings 21 insulated from each other. The rings 2 and 3 are made of nonferromagnetic metal such as bronze or stainless steel and have a number of holes 8 equidistantly spaced on their inside edges. Conducting copper wires 5 are netted through these holes 8 in such a manner that the wires inclined by

$$\tan \theta = \frac{1}{\sqrt{2}}$$

relative to the planes of said rings 2 and 3 and produce a hyperboloidal side-surface E such as shown in FIG. 4. If one denotes by section $2l$ the diameter of a circle, which is the intersection of the hyperboloid of one surface with a plane equidistant from said rings 2 and 3, the equation of the hyperboloid becomes

$$x^2 + y^2 - 2e^2 = l^2$$

As explained throughout the specification, the function of the net of conducting copper wires is as follows:

The net of conducting copper wires forms the side surface of the hyperboloid of one sheet. If the potential of the hyperboloidal electric field is

$$\frac{V}{4}(-x^2 - y^2 + 2e^2)$$

the side surface should be maintained at the constant potential which is produced by the apparatus shown in FIG. 7. This potential equals the potential of the rings furthermost from the centers mounted on the upper and lower discs. On each of the insulating discs (upper 7 and lower 6), shown in FIG. 5, a number of concentric circular copper rings 21 are mounted equidistantly and maintained at appropriate potentials.

The discs on which the concentric copper rings are mounted are insulating materials and the concentric copper rings are insulated from each other. The concentric copper rings are maintained at appropriate potential by the apparatus shown in FIG. 7.

If φ_0 is the potential at the center of the disc, φ_1 the potential at the ring 2 or 3 and n the number of concentric rings 21 on each disc, the proper potentials to apply to the concentric rings 21 on each disc will be as the following: as

$$\varphi_0 = \frac{d^2}{2l^2} V, \varphi_1 = -\frac{V}{4}$$

where $2d$ denotes the vertical distance of said rings 2 and 3.

An ion source, that is, means for omitting ions, comprises pipe 9 having a window 24 and inner pipe 25, shown in FIG. 6. Pipe 25 is insulated from pipe 9 by means of Pyrex glass. Pipe 9 passes through disc 6 by hole 23 perforated through disc 6, as shown in FIG. 5, and disc 7 by a hole perforated therethrough, inclining at an angle 35.25° for the disc plane. An ion starting from window 24 in a plane parallel to the discs 6 and 7 travels a path such as shown in FIGURE 1 in the same plane, but an ion starting from window 24 in an outward direction from the plane goes apart from the plane, and returns to the plane to collide upon detector 26. If there is no detector, the ion oscillates up and down about the plane, while the projection of the ion on the plane travels a path such as shown in FIGURE 1. Since the electric potential is constant on any hyperboloidal surface $x^2 + y^2 - 2e^2 = k$, k const., the electric potential is also constant along any generator of the hyperboloidal surface, and any generator inclines at an angle $0 = 35.25^\circ$, determined by the relation $\tan \theta = 1/\sqrt{2}$, for the disc plane. Window 24 is substantially on the median plane equidistant from the upper disc 7 and the lower disc 6. Inner pipe 25 has a gap inside window 24.

An ion detector or collector, that is, means for detecting or collecting ions, comprises pipe 10 having window 26 and inner pipe 27 and is of the same shape as said ion source except that inner pipe 27 has no gap. Pipe 10 is insulated from pipe 10 by means of Pyrex glass. Pipe 10 is positioned at a position, which is reached by pipe 9 after a rotation by an angle 40.5° around the symmetrical axis of said electrode and a reflection with respect to said median plane, as shown in FIG. 3. Pipe 10 passes through disc 6 by hole 22 perforated therethrough, and disc 7 by a hole perforated therethrough. Window 26 is substantially on said median plane. Projections of parts of pipe 9 and pipe 10 on the plane of disc 6 are shown as 32 and 33 respectively in FIG. 5.

The emission of ions is effected as follows. A low voltage is developed across said gap of inner pipe 25 and an electron beam is formed between said gap. Molecules of a sample to be analyzed are introduced within inner pipe 25, ionized at said gap, accelerated by a potential difference between pipe 9 and pipe 25, and drawn out through window 24. After traversing arcuate paths, ions

having the desired mass-to-charge ratio converge to pipe 27 through window 26. Ions which have not the desired mass-to-charge ratio and are not collected by the ion collector travel around the symmetrical axis of said electrode to impinge finally upon a screen 41.

The screen 41 shown in FIGURES 2, 3 and 5 is an insulating rectangular plate equipped with a plurality of rectilinear conducting wires 42, inclining at an inclination of 35.25° for the disc plane. Three sides of screen 41 are limited by said electrode, the other side of screen 41 passes the center of said electrode. The position of screen 41 is shown by the projection 51 in FIG. 5 of screen 41 on disc 6 and by an elevation of screen 41 in FIG. 3. Each of rectilinear conducting wires 42 shown in FIG. 5 of screen 41 connects one of concentric rings 21 on disc 15 to one of concentric rings of disc 7.

The ions that impinge upon the electrode and screen 41 will lose their energy and charge and are to be pumped out by a pumping system. On the bottom of the tank 1 are provided a positive terminal 11 and a negative terminal 12 for the electrode, a terminal 16 for the ion current detector or collector and terminals 13, 14 and 15 for the ion source.

In order to measure ions of various mass-to-charge ratio, magnetic field strength B or potential difference V is to be varied so as to satisfy the relation

$$\frac{m}{e} = \frac{B^2 l^2}{6V}$$

If one puts $v=4\lambda$, therefore $\omega=3\lambda$, one has $\xi=\xi_0$, $z=z_0$, at $t=\pi/\lambda$.

All ions starting from any point (ξ_0, z_0) at the time of $t=0$ converge therefore to the starting point at the time of $t=\pi/\lambda$ and perform a periodic motion with the period of π/λ .

In this case the relation of magnetic field strength B and potential difference V is as follows:

$$\frac{m}{e} = \frac{4B^2 l^2}{9V}$$

A D.C. power supply can be constructed according to a well-known model described in a book by William C. Elmore and Matthew Sands, entitled: Electronics—Experimental Techniques, 1949 edition.

When a D.C. power is supplied through a potential divided to the electrode, there results a hyperboloidal electric field in a space defined by said electrodes.

While the salient features of this invention have been described in detail with respect to one embodiment it will of course be apparent that numerous modifications may be made within the spirit and scope of this invention and it is therefore not intended to limit the invention to the exact details shown except insofar as they may be defined in the following claims.

What is claimed is:

1. A mass spectrometer comprising means to produce a uniform magnetic field; means to produce a hyperboloidal electric field including an electrode; said electrode comprising a pair of parallel insulating discs, facing each other, perpendicular to the direction of said magnetic field; a plurality of concentric conducting rings

insulated from each other mounted to said discs; a pair of circular rings, each of said circular rings being connected to the outermost ring of each of said parallel insulating discs; a net of a hyperboloidal surface constructed with conducting wires connecting said pair of circular rings; means energizing said electrode to provide a hyperboloidal electric field within a space defined by said electrode, an ion source and an ion detector-collector positioned within said space.

10 2. A mass spectrometer as claimed in claim 1, comprising in addition a screen of an insulating plate including a plurality of conducting wires connecting separately a plurality of concentric conducting rings of one disc of said pair of discs to a plurality of concentric conducting rings of the other disc of said pair of discs, said screen being positioned within said space and limited by said electrode and by a plane perpendicular to said discs and passing the center of said electrode.

20 3. A mass spectrometer comprising in combination an evacuated tank, means to produce a hyperboloidal electric field within said tank including an electrode, means to produce a uniform magnetic field in parallel with the symmetrical axis of said electrode and an ion source and an ion current detector within said electric field.

25 4. A mass spectrometer comprising in combination an evacuated tank means to produce a hyperboloidal electric field including an electrode, said electrode comprising a pair of concentric rings of conducting wires facing each other and a net of a hyperboloidal surface constructed with conducting wires connecting the outer rings of said pair of concentric rings, means to produce a uniform magnetic field in parallel with the symmetrical axis of said electrode and an ion source and an ion current detector within said electric field and said magnetic field.

35 5. A mass spectrometer comprising in combination means to produce a hyperboloidal electric field including an electrode, and means to produce a uniform magnetic field in parallel with the symmetrical axis of said electrode, in the relation of

$$\frac{m}{e} = \frac{B^2 L^2}{6V}$$

as m , mass; e , charge; B , magnetic field strength, L , length measuring the dimension of electrode; and V , potential difference, means to focus ions of like mass-to-charge ratio, including an ion source and an ion current detector, said ion source and said ion current detector mounted at an image position of said ion source within said fields and an evacuated tank forming a housing for said electric field, said magnetic field, said ion source and said ion current detector.
